188,583

COMBINED CARRYING CASE AND TRAY

Charles William Moss, 1415 Beechwood Drive,
Ann Arbor, Mich.

Filed Dec. 15, 1959, Ser. No. 58,665

Term of patent 14 years

(Cl. D87—5)

Fig. 1.

Fig. 2.

Fig. 3.

Fig. 4.

Fig. 1 is a front perspective view of a combined carrying case and tray showing my new design;

Fig. 2 is a top plan view;

Fig. 3 is a front elevational view;

Fig. 4 is a side elevational view;

Fig. 5 is an enlarged scale, top plan view, with the tray-door in open condition, a portion broken away for convenience of illustration; and

Fig. 6 is an enlarged scale, perspective view thereof, with the carrying handle and tray-door in open condition.

I claim:

The ornamental design for a combined carrying case and tray, as shown and described.
